UNITED STATES PATENT OFFICE.

WILLIAM A. MILLER, OF RICE LAKE, WISCONSIN.

BRUSH ATTACHMENT.

1,162,635.

Specification of Letters Patent. Patented Nov. 30, 1915.

Application filed June 3, 1915. Serial No. 31,945.

To all whom it may concern:

Be it known that I, WILLIAM A. MILLER, a citizen of the United States, residing at Rice Lake, in the county of Barron and

5 State of Wisconsin, have invented certain new and useful Improvements in Brush Attachments; and I do hereby declare the following to be a full, clear, and exact description of the invention, such as will enable 10 others skilled in the art to which it appertains to make and use the same, reference being had to the accompanying drawings, and to the letters and figures of reference marked thereon, which form a part of this 15 specification.

This invention relates to certain new and useful improvements in brushes and it relates more particularly to that class of 20 brushes designed for use in attaching wall paper, advertising bills, etc., and it has for its object the provision of a simple and efficient form of scraper so attached to the head of the brush as to adapt it for use in removing the paper and for clearing the 25 surface to which paper is to be attached.

The invention has for a further object the provision of an attachment of this character 30 so constructed as to provide cutting or scraping edges, adapted for use in the upward or downward movement of the brush.

To these ends and to such others as the invention may pertain, the same consists in the novel form of a concaved, double edged cutting plate adapted to be attached to the 35 side of the brush head, as will be more fully hereinafter described, shown in the accompanying drawings and then specifically defined in the appended claim.

My invention is illustrated in the accompanying drawings which, with the numerals of reference marked thereon, form a part 40 of this specification and in which:

Figure 1 is a perspective view of a paste brush provided with my scraper attachment. Fig. 2 is a vertical section of the same. Fig. 45 3 is a detail view in perspective of the concaved cutting plate.

Reference now being had to the details of the drawings by numeral, 1 represents 50 the brush which is of ordinary construction,

consisting of the head 2 and bristles 3, comprising the brush proper, the brush being attached to the head in any approved manner.

4 is a metallic plate of a length substantially the length of the brush head. This plate is concaved as shown with the opposite edges curved slightly outwardly, each of the edges being provided with a cutting or scraping edge, as shown. The plate is bolted or otherwise securely attached to the one face of the brush head, as shown in the drawings, either by screws, bolts or other suitable attaching means.

From the foregoing description, the advantages derived from the use of the attachment will be readily understood.

The upper and lower cutting edges of the plate, being inclined outward, renders it possible for a person, when applying paper 70 to walls or bill boards, to readily remove the paper adhering to the surface to be repapered by simply inclining the head of the brush so as to bring the cutting or scraping plate into contact with the surface to be papered 75 and, by either moving the brush upward or downward as the circumstance may require, the surface can be readily cleared of paper adhering to the surface.

It will be noted that in moving the brush 80 head upward, the upper cutting edge of the plate will, by the upper movement of the brush, be removed from the surface, whereas the downward movement will bring the lower cutting edge of the plate in use. 85

What I claim to be new is:—

In combination with a brush having a head with a band about the same, a channeled plate fastened to said band and head and extending substantially the length 90 thereof, said plate having its opposite edges curved, the longitudinal edges of which are in a plane parallel with the face of the head and spaced apart therefrom.

In testimony whereof I hereunto affix my 95 signature in presence of two witnesses.

WILLIAM A. MILLER.

Witnesses:

C. E. OVERBY,
P. PETERSON.
